Specification for Design.

Patented Sept. 15, 1914.

Application filed March 13, 1914. Serial No. 824,560. Term of patent 14 years.

To all whom it may concern:

Be it known that I, ALLEN C. SELLECK, a citizen of the United States of America, and a resident of Chicago, in the county of Cook and State of Illinois, with a post-office address at 1924 West Madison street, in said Chicago, have invented a new, original, and ornamental Design for Pancake-Turners, of which the following is a specification, reference being had to the accompanying drawing, forming part thereof.

Figure 1 is a perspective view of a pancake turner showing my new design. Fig. 2 is an end view of the same.

I claim:

The ornamental design for a pan cake turner as shown.

ALLEN C. SELLECK.
